PALLET CONSTRUCTION FOR SINTERING APPARATUS

Victor F. Koontz, Moon Township, Allegheny County, Pa., assignor to Dravo Corporation, Pittsburgh, Pa., a corporation of Pennsylvania

Filed June 6, 1958, Ser. No. 740,317

2 Claims. (Cl. 266—21)

This invention relates to sintering apparatus and is for an improved pallet or tray construction for use in down draft sintering apparatus.

In down draft sintering apparatus, the pellets to be burned or sintered are deposited on a succession of traveling trays or pallets that move progressively over a succession of suction chambers, or wind boxes, so that the charge, after being ignited, is supplied with air drawn down through the charge. These trays or pallets are in reality each a small car rolling or sliding on rails at each end of the pallets, each car abutting against the one ahead to form in effect, a continuous traveling support. They are rectangular in shape with their greatest length crosswise of the direction of travel. They have strength members extending in the direction of their length, which members are flanged at the top. A system of grate bars extending crosswise of the length of the pallet are interfitted with these flanged members to support the charge which is to be burned.

In a typical operation, the top flange of the supporting or strength bars may reach a temperature of 1500 to 1900° F. while the bottom flanges of the same members are more nearly that of the combustion gases in the neighborhood of 1100 to 1300° F.

Warping of the trays has been a constant problem, since after a period of use they sag from the ends toward the center. Various efforts have been made to correct this without success, although it has been a persistent and costly weakness. Among other things, it has been proposed to use more massive strength members. It has also been proposed to use alloys for the strength members. A further unsuccessful expedient has been to provide air chambers in the strength members to lower the temperature of the critically stressed metal.

Since sagging could not be corrected, one expedient is to make them reversible and allow them to sag in one direction, turn them over, and let them sag in the other direction. Another plan is to make them in two sections and bolt them together at the middle. When sagging occurs, the bolts are loosened and shims are used between the sections to try to correct warping.

I have determined that sagging is not due merely to the overheating of a beam section while under uniform load, but that by reason of the non-linear temperature differential that exists at the top and the bottom of the beam a high stress is induced in the flange at the top which supports the grate bars as it attempts to expand under the greater heat and this expansion is restrained by the cooler metal at the bottom of the section. This results in compressive forces in the top flange sufficient to upset or warp it, so that when the pallet cools to a point where the top and bottom flange are at equal ambient temperature, the top is shorter than the bottom, resulting in a downward curve from the ends toward the middle.

My invention has for its principal object to provide a pallet construction in which thermal stresses such as produce warping will be avoided. A further object of

2

my invention is to provide a construction in which the beams will be subjected to more nearly uniform temperature at the top and bottom. A still further object is to provide a pallet of improved construction.

These and other objects and advantages will be apparent to those skilled in the art from the following description of my invention in conjunction with the accompanying drawings, in which:

Fig. 1 is a front elevation of one end of a pallet embodying my invention, it being understood that the opposite end is a counterpart thereof, and for clarity of illustration only one end has been shown;

Fig. 2 is a fragmentary transverse vertical section in the plane of line II—II of Fig. 1 with the grate bars indicated by dot-and-dash lines;

Fig. 3 is a fragmentary top plan view of an area of the pallet showing my invention; and

Fig. 4 is a longitudinal vertical section in the plane of line IV—IV of Fig. 3.

Referring to the drawings, the pallet comprises a carriage which is essentially a beam of rectangular section. The arrow in Fig. 2 indicates the direction of travel of the pallet. At each end of the carriage there is a transition plate 2 to which is secured a casting 3 that carries the shaft for supporting the wheels 4 that support the pallet on the track (not shown) along which the pallet moves, the transition plate abutting against an end plate 2a. There is a side plate 5 on this casting to retain the bed of material on the pallet, and 6 designates the usual seal that rides along the top of the wind boxes.

I have shown the carriage as being fabricated from welded metal plate. Along each longitudinal edge of the pallet is a channel section 7 having a vertical web 7a, a top flange 7b, and a bottom flange 7c (see Fig. 2).

These channels extend between and are welded to the end plates 2a. Spaced between the channels 7 are one or more I-beam sections 8 having a vertical web 8a, a top flange 8b, and a bottom flange 8c. These I-beam sections are also welded to the end plates 2a. The channels and I-beams are tied together in parallel relation not only at the ends by the end plates 2, but at intervals along the length of the pallet by cross members of I-beam section, designated 9 in Figs. 3 and 4. The number of I-beams 8 and the number of cross connections 9 depends upon the size of the sintering apparatus and is not material to the present invention, but there should be a maximum open area through which combustion gases can be drawn, and it will of course be apparent that this structure could be an integral casting.

Thus the carriage comprises a composite beam of rectangular section formed of parallel sections connected at their ends and intermediate points. Bolted to the top of this composite frame are a plurality of parallel angle sections 10, the bolts for securing them being designated 11. The vertical webs 10a of these angles have horizontally elongated slots 12 therethrough. Placed against and bolted to each of these vertical webs 11a of the angles are the vertical webs of composite flanged bars 13 and 14, the bars 13 being at the longitudinal side edges of the structure and having a horizontal flange 13a that extends toward the longitudinal center of the structure, while the bars 14 have flanges 14a that extend in both directions. The flanges 13a and 14a fit into notches in the ends of the replaceable grate bars 15 that extend in a direction transverse to the length of the pallet, and in this manner support and retain the grate bars in the structure.

The flanged bars 13 and 14 are secured to the vertical webs 11a of the angles by bolts 16 passing through the bars and through the slots 12 in the vertical webs, with nuts 16a that are taken up firmly but not too tight. This provides a friction clamp connecting the flanged bars and the angles.

From the foregoing it will be seen that the grate bars are supported on composite carrying structures extending lengthwise of the pallet in which the top portions 13 and 14 are separate from the bottom beam sections 7 and 8 respectively, forming rigid beams in which the top can expand and contract independently of the bottom by reason of the bolts 16 passing through horizontally slotted openings in one part of the composite structure. The ends of the top bar portions 13 and 14 are not confined, so that expansion and contraction of these portions relatively to the supporting structure below is confined only by the tightness of the bolts and nuts 16—16a.

Also there are two bolted connections, one between the bars 13 and 14, and the vertical webs of the angles 11, and the second between the bases of the angles 11 and the tops of the main pallet frame. Since these afford a poor path of heat conductivity, there is less heat carried by conduction into the top parts of the channels 7 and beams 8, and they therefore are at a more nearly uniform temperature during the sintering of the charge on the grates, this being closer to the temperature of the combustion gases.

By reason of this construction, therefore, a pallet is provided in which sagging and cracking is greatly reduced or entirely eliminated, thereby getting rid of one of the heretofore troublesome problems encountered in apparatus of this kind.

I claim:

1. A pallet for sintering machines comprising a rigid frame having like top and bottom surfaces so that either may be used by turning it over, the frame being of rectangular transverse section and having two end members with spaced parallel beams connecting the end members, the spaces between the beams being open for the passage of air through the pallet, the uppermost surface of the frame having a plurality of angle bars releasably secured thereto with one leg of each bar supported on the uppermost surface of the frame and having one leg portion extending vertically, a flanged grate-supporting bar having a vertical web portion bolted to the vertical leg portion of each of said angle bars by bolts passing through the respective vertical leg portions of the grate-supporting bar and the angle bar, one of the leg portions so bolted together being longitudinally slotted for the passage of bolts therethrough but allowing relative expansion and

contraction of one leg portion lengthwise to the other, and grates having grooved ends interfitting with the flanges of the grate-supporting bars, said flanges and grates being in a plane spaced above the uppermost surface of the rigid frame.

2. A pallet for sintering machines comprising a main supporting frame having like top and bottom surfaces so that it may be reversed, said frame having spaced parallel beams extending longitudinally of the pallet and joined at their ends by end plates, said frame being open for the passage of gases or air therethrough, parallel flanged grate-supporting structural assemblies removably secured to the tops of said beams and resting thereon with their ends clear of the end plates of the main frame, each said assembly having one longitudinally-extending structural lower section resting on and secured to the beam along which it extends by a bolted connection, each said assembly having a longitudinally-extending upper structural section with a horizontal flange at the top thereof and secured to the lower section below the flanged top by a bolted connection, the upper member of each said assembly being thereby connected with the beam along which it extends through an intervening structural section and through bolted connections at two levels, the bolted connections at one level having longitudinally-elongated bolt holes to enable the upper section to expand and contract lengthwise relative to the beam along which it extends, and transverse grates extending crosswise of the pallets between the flanged upper sections of the assemblies, the grates having bifurcated ends engaging the flanges of the upper sections, the grate bars being elongated by the grate-supporting assemblies entirely above the top of the main supporting frame.

CERTIFICATE OF CORRECTION

Patent No. 2,985,440

May 23, 1961

Victor F. Koontz

It is hereby certified that error appears in the above numbered patent requiring correction and that the said Letters Patent should read as corrected below.

Column 2, line 56 and lines 66 and 67, for "vertical webs 11a", each occurrence, read -- vertical webs 10a --; column 3, line 15, for "11", both occurrences, read -- 10 --; column 4, lines 31 and 32, for "elongated" read -- elevated --.

Signed and sealed this 7th day of July 1964.
